UNITED STATES PATENT OFFICE.

FRANCIS H. ESCHERICH, OF WASHINGTON, DISTRICT OF COLUMBIA.

NURSING-BOTTLE HOLDER.

1,040,659.

Specification of Letters Patent.

Patented Oct. 8, 1912.

Application filed May 29, 1912. Serial No. 700,435.

To all whom it may concern:

Be it known that I, FRANCIS H. ESCHERICH, a citizen of the United States, residing at Washington, District of Columbia, have invented certain new and useful Improvements in Nursing-Bottle Holders, of which the following is a specification.

This invention relates to new and useful improvements in nursing bottle holders, and more particularly to that class adapted to support a nursing bottle in a convenient position above a high-chair, crib or the like, within the easy reach of the child resting therein.

An object of this invention is the provision of a holder such as described which employs the use of a spring locking clamp adapted to yieldingly engage a bottle and support the same in its proper position against any undesired vertical, lateral or longitudinal displacement.

Another object of this invention is the provision of a nursing bottle holder which can be adjusted to any desired position, relative to its support.

Still another object of this invention is the provision of a nursing bottle holder of an extensible type, which can be lengthened or shortened to accommodate bottles of various sizes.

A further object of this invention is to improve and simplify devices of this nature, which will be comparatively simple and inexpensive to manufacture, reliable and efficient in use and readily operated.

With the above and other objects in view, this invention resides in the novel features of construction formations, combinations, and arrangements of parts to be hereinafter more fully described, claimed and illustrated in the accompanying drawings in which:—

Figure 1. is a side elevation of my invention. Fig. 2. is a top plan view thereof. Fig. 3. is a longitudinal sectional view thereof. Fig. 4. is a detail view of one of the attaching clamps, Fig. 5. is a rear elevation with parts broken away.

Referring to the accompanying drawing by similar characters of reference, the numeral 10 denotes in general my improved nursing bottle holder, comprising a main standard 11, which is slidably located in the spaced alining eyes 12 formed upon a clamp 13, by means of which the holder can be attached to a suitable support such as a

high-chair, carriage, crib, or the like. One of the eyes is formed with a threaded opening, through which a set screw 14 is passed to retain the standard in its various adjusted positions.

A swinging arm 15 is pivoted to the upper end of the standard 11, and locked against movement by the winged nut 16, which is threaded on the pivot bolt 17, and riveted to this arm 15 is an arcuate plate 18 arranged to form a rest for the bottle 19. A similar plate 20 rests in the channel formed by the concaved face of the plate 18, and has projecting from its lower side in longitudinal alinement, a pair of spaced studs 21, which project through a slot 22 formed in the plate 18. One of these studs is threaded while the other is formed with a T head 23 which overlaps the opposite edges of the slot 22 and holds the two plates against displacement. A winged nut 24 is threaded on one of the said studs, while in order to provide for the disconnection of the plates the end of the slot 22 is enlarged as at 25 to permit of the passage of the head 23 therethrough. This construction permits the plates to be lengthened to accommodate the bottles of various sizes.

A strap 26 is connected to the outer end of the plate 20 and produces a yoke for reception of the neck of the bottle, while secured to the opposite end of the plate 18 is a spring clamp 27, the opposite arms 28 of which are curved upwardly, rearwardly and inwardly to grasp the base of the bottle and hold the same against any upward or rearward displacement.

Special attention is called to the specific construction of the arms 28. It should be noticed that they are curved over the rear end of the bottle and spaced apart to produce a converging guide way 29, which when the neck of the bottle is inserted through the yoke, and pressure exerted upon the opposite end thereof, the said arms will be forced outwardly and the bottle securely clamped against undesired displacement by the said arms 28 which by their resiliency will firmly grasp the opposite sides and rear end of the bottle.

It should be understood in this connection, that various minor changes in the details of construction can be resorted to within the scope of the appended claim, without departing from or sacrificing any of the advantages of the invention.

From the foregoing it will be manifest that a nursing bottle holder is provided which will fulfil all the necessary requirements of such a device.

5 Having thus fully described this invention, what I claim as new and desire to protect by Letters Patent is:—

In a nursing bottle, the combination with a standard, of a clamp rotatable and 10 slideable thereon, means for rendering the clamp rigid upon the standard, an arm pivoted to the standard, means for rendering said arm rigid relative to the standard, a plate secured to said arm, a second plate adjustable

upon the first plate, means for rendering 15 said plates rigid; a yoke carried by one plate, and a spring clamp secured to the other plate, said clamp comprising a pair of curved spring arms adapted to be parted by the pressure of a bottle therebetween to 20 grasp the bottle and engage the opposite sides and end thereof.

In testimony whereof I affix my signature in presence of two witnesses.

FRANCIS H. ESCHERICH.
